COMBINED TOY TRACTOR AND PLOW

Gerald W. Schmidt, Woodland Hills, and Anson Sims,
Redondo Beach, Calif., assignors to California R & D
Center, Pacific Palisades, Calif.

Filed Mar. 2, 1972, Ser. No. 231,441

Term of patent 14 years

Int. Cl. D21—01
U.S. Cl. D34—15 AN

FIG. 1 is a perspective view of the combined toy tractor and plow of the present invention; and

FIG. 2 is a perspective view of the combined toy tractor and plow illustrating the back side thereof.

We claim:

The ornamental design for a combined toy tractor and plow, substantially as shown and described.
